KNIFE SHARPENER

James A. Murdock, Chicago, Ill.

Application June 18, 1938, Serial No. 214,522

1 Claim. (Cl. 76—86)

This invention relates to knife sharpeners and has for its principal object the provision of a simple and effective knife sharpener which can be very readily constructed and operated.

The invention will readily be understood from the following description of a preferred embodiment thereof taken in conjunction with the accompanying drawing, in which:

Fig. 1 is a perspective view of a sharpener embodying the invention being used,

Fig. 2 is an elevation thereof,

Figs. 3 and 4 are fragmentary elevational views showing the relation of the sharpening plates during use,

Fig. 5 is a sectional plan view taken on the line 5—5 of Fig. 3, and

Fig. 6 is a similar view taken on the line 6—6 of Fig. 3.

Referring to the drawing, the sharpener comprises two similar plates 10 of hard tool steel or other suitable metal of requisite hardness. Each plate 10 comprises a main body portion 11 and a strip portion 12 which is in alignment with the lower marginal portion of the main body portion 11.

Each of the plates 10 is riveted or otherwise suitably secured to the flattened end 13 of a bail-like handle 14. This handle may suitably be formed from a stout metal rod which is bent 30 into bail-like form and is preferably waisted to provide a suitable handle, whereby the sharpener may be firmly held during use.

As will be clearly seen in the drawing, the two plates 10 are located in opposition with each lower extension or strip portion 12 overlying the lower portion of the main body portion 11. For this reason the two plates 10 are located in adjacent vertical planes as shown in Figs. 5 and 6. Each of the strip portions 12 has rigidly mounted thereon a rivet 15 which extends freely through a slot 16 in the body portion 11 of the other plate 10. The openings 16 are elongated in the transverse direction of the tool as best seen in Figs. 3 and 4 to provide for a slight relative motion between the plates.

The edge 17 of each of the plates 10, that is the

inner edge of the main body portion 11, which extends upwardly from the projecting portion 12, is located approximately in the axis of the tool and it slopes outwardly to a slight extent relative to that axis. The two edges 17 overlie and cross each other as shown in Figs. 2, 3 and 4. The ends of the handle 14 are biased inwardly so that the rivets 15 are normally located in the outer ends of the slots 16. When the plates 10 are in this relative position, the two edges 17 provide a small V for the reception of the edge of a knife which is to be sharpened. When the knife is pressed into the slot the plates 10 are forced relatively outwardly to a slight extent and the rivets 15 move to the inner ends of the slots 16 as shown in Fig. 4.

In operation the handle 14 is grasped by one hand and the knife is inserted in the V slot and drawn forwardly. The handle should be inclined forwardly at a slight angle. As weight is applied to the knife it is forced more deeply into the V slot enlarging the same. Thus considerable pressure is applied to the cutting edges 17 and the location of the sharpening is varied continuously, whereby localized wear on the edges 17 is avoided.

Although the invention has been described in connection with the specific details of a preferred embodiment thereof, it must be understood that such details are not intended to be limitative of the invention except as set forth in the accompanying claim.

Having thus described my invention, I declare that what I claim is:

A knife sharpener comprising two plates in adjacent and partially superposed relation, said plates having overlapping and relatively inclined edges forming an acute V slot, rivet means connecting said plates to provide limited sliding relative movement to enlarge and contract said slot, said rivet means passing through a hole in one plate and an overlying slot in the adjacent plate, and a bail-like handle having its ends secured to said plates whereby the handle when grasped tends to move the plates to contract the slot.

JAMES A. MURDOCK.
